*J. Harrison,
Dental Mold.*

No 8312.

Patented Aug. 26, 1851.

UNITED STATES PATENT OFFICE.

JAMES HARRISON, OF JAMESTOWN, NEW YORK.

IMPROVEMENT IN DENTAL HYDRAULIC CUPS.

Specification forming part of Letters Patent No. 8,312, dated August 26, 1851.

To all whom it may concern:

Be it known that I, JAMES HARRISON, of the village of Jamestown, in the county of Chautauqua and State of New York, have invented a new and useful Machine called the Dental Hydraulic Cup; and I do hereby declare that the following is a full, clear, and exact description of the construction and operation of the same, reference being had to the annexed drawing, making a part of this specification.

My machine is made of silver or some similar material; and it consists of a fountain-pipe, marked *b* in the annexed drawing, which is attached to the plate marked *c* (under plate) and is inserted through the same; also, the discharging-pipe marked *e* is inserted through plate *c* immediately under the fountain-pipe *b*. On the inner side of plate *c* and immediately below the lower end of the pipe *b* is the division-plate *d*, (center plate,) soldered at the upper edge and sides to the plate *c*, to be left open and unconnected at the lower edge only. The plate *f* (upper plate) and plate *c* are soldered around the outer edge to a wire. A space of about one-eighth of an inch is left between plates *d* and *f* and about the same space between plates *d* and *c*, which altogether constitute a perfect instrument, (the said plates being united in a concave form,) marked No. 1 in the annexed drawing, and is calculated to be applied to the upper jaw of the mouth, into which concave the material to be impressed is placed and there held until the impression is perfected. Then at the head of the fountain-pipe marked *b* let the water be applied, which first fills the aperture between plates *d* and *f* and discharges at the bottom or unconnected part of plate *d* and fills the aperture between plates *d* and *c*, and then discharges through the pipe *e*. I keep a continual current of water running through the said machine and the apertures between the said plates filled, and to conduct to that end the pipe *b* should be larger than pipe *e*, and cold or warm water may be applied, according to the kind of temperature required. For instance, I would apply cold

water to beeswax and warm water to a preparation of plaster-of-paris. The object accomplished thereby is to harden and render more firm the material impressed before it is withdrawn from the jaw.

My machine to be applied to the lower jaw is in all respects like the one above described, (the form of the plates being slightly varied, so as to apply properly to the same,) except the fountain-pipe *b* and the discharging-pipe *e* are inverted, as seen in the plate marked No. 2 in the annexed drawing.

Numbers 3 and 4 in the annexed drawings represent my machine No. 1 divided longitudinally in the center and are calculated to show the course of the current of water, the opening of the pipes, the connection of the same to the plates, and the vacancies between the plates.

The drawing marked *h* represents plates *c* and *d* united.

The gate marked *g* in the drawing is to be used only in taking impressions of the upper jaw, and is attached to the lower edge of the plate marked *f* by means of a hinge, and when applied to the mouth is turned into the plate *f* and holds the material to be impressed in its place and prevents the same from penetrating into the throat. It has no connection with the course or discharge of the water.

What I claim as my invention is—

1. The construction of said machine of two or more plates with vacancies between the same and with pipes annexed thereto.

2. The application of water or any suitable liquid to the space or vacancy between the plates for the purpose of hardening and rendering more firm the contents of the cup while on the jaw.

3. Nothing for the outward form of the said plates nor for the application of the same to the mouth merely to take impressions, but the method of using the gate, as described.

JAMES HARRISON.
